4 Claims. (Cl. 112—2)

The present invention relates to a new type of machine for the lateral sewing of the soles of jute and similar materials, and of the jute soles with toe piece and welt jointly, with or without shoe mould, and it is an essential object of this invention, to provide a machine enabling the economical manufacture of shoes of the class known as jute and canvas shoes of any type and shape.

The invention embodies also other objects that will appear in the course of the following specification, considered in connection with the accompanying drawings.

In these drawings:

Figure 1 is a general view of the machine in front elevation and showing a part of the mechanism.

Figure 2 is a partial detail of the machine in section through a line 2—2 of Figure 1.

Figure 3 is a view of the plate for pressing the sewing, associated with the embodiment of Figure 2.

Figure 4 is an elevation of the element shown in Figure 3, showing the application of the guiding rollers for the displacement of the shoe mould.

Figure 5 is a section through the line 5—5 of Figure 1, showing other elements of the mechanism.

Figure 6 is a detail, in section, through the line 6—6 of Figure 1, showing other details of the mechanism.

Figure 7 is an elevation of the right side of the machine, partly in section.

Figure 8 is a section on the line 8—8 of Figure 1, showing other details of the mechanism.

Figure 9 is a section on the line 9—9 of Figure 1, showing other details of the mechanism.

Figure 10 is a vertical section on the line F—F of Figure 7.

Figure 11 is a detail section on the line 11—11 of Figure 10.

Figure 12 is a detail horizontal section on the line 12—12 of Figure 10.

Figure 13 is a section on the line 13—13 of Figure 10, showing another detail of the mechanism.

Figure 14 is a sectional view of the machine on the line 14—14 of Figure 10.

Figure 15 is a section through the line 15—15 of Figure 14.

Figure 16 is a general view, in section of the left side of the machine.

Figure 17 is a section on the line 17—17 of Figure 16.

Figures 18, 19, 20 and 21 are details of the mechanism forming the machine.

Figure 22 is a view in side elevation of the pressing means.

Figure 23 is a partial plan of the driving device for the pressing means.

Figure 24 is a partial section on the line 24—24 of Figure 23.

Figure 25 is another partial section on the line 25—25 of Figure 23.

Figure 26 is a plan view of the upper frame of the pressing arrangement.

Figure 27 is a front elevation view of the pressing arrangement.

Figure 28 is a diagrammatic side elevation and section through the line 28—28 of the Figure 23, showing the general assembly of the pressing means.

Figure 29 is a fragmentary detail of part of the elements forming the pressing arrangement.

Figures 30 and 31 are other fragmentary details of part of the elements forming the pressing arrangement, in different positions.

Figure 32 is a partial plan view of the machine, showing the automatic driving means for stopping the needle out of contact with the sole or the like.

Figure 33 is a partial view of the machine, in side elevation, showing the embodiment shown in Figure 32.

Figure 34 is a partial view, taken from the rear of Figure 32.

Figure 35 is a fragmentary section, in lengthwise section, of parts shown in Figure 32.

Figure 36 is a section on the line 36—36 of Figure 35.

Figure 37 is a section on the line 37—37 of said Figure 35.

Figure 38 corresponds with Figure 37, with the movable elements that form same, in different position.

Figure 39 is a schematic view, in perspective, of the brake elements showing their operation more clearly.

Figures 39a, 40, 41 and 42 have been added to illustrate the work of the machine on the independent sewing of the soles of jute, hemp or similar material, or in the sewing of the soles with toe piece and welt jointly.

Figure 39a is a perspective of the sole of jute and similar material, before sewing, having the said material marked y.

Figure 40 is a perspective of the sole illustrated in the former figure, after having been

compressed and sewed with thread *z* which goes all through the sole.

Figure 41 is a perspective view, before sewing of the addition of the sole to the toe piece *k* and the welt *w* which will constitute the canvas shoe.

Figure 42 is a view of the finished canvas shoes obtained after the embodiment illustrated in the former figure, has been compressed and sewed to the lateral sewing by means of thread *q*.

The machine according to the present invention, is made up as follows: A supporting frame *1*, from the upper plan *2* of which projects, at its front side, a partition *3*, on which at its rear side, are provided the driving elements for the needle and punch, and in proper working relation the rotative punch, as well as the driving means for the shuttle. All these elements are synchronized with the mechanism that drives the pressing elements and with the elements for braking the needle, that will be all described in numerical order and separately, for the purpose of giving a clear disclosure of the machine. For convenience the description will commence with the means that drive the needle, comprising its punch and the turning punch, which carry a rocking element *4* (Figure 10) mounted for free pivotal movement by one of its ends on a support *5*, that is secured to the partition *3*, by means of a shaft or pivot *6*. The rocking element *4* is connected at its other end with free pivotal movement to the lower, fork shaped end, of a cam arm *7*, which is connected at its other end to a sliding member *8*, mounted for freely sliding between lateral guides *9* (Figures 1-5 and 10) which have their lateral sides, dovetail shaped; the said guide members being fixed to the partition. The sliding member forms the carrying element for the needle *11* and the punch *12*, to which pieces is transmitted the rectilineal vertical alternative movement of the sliding member, and the said elements *11*-*12* are connected to the lower end of the sliding member *8*, through a support *13*, detachably secured to the lower side of the sliding member *8*.

The rocking member *4* is provided with a grooved portion, at the middle point *14* (Figures 10-11 and 32) in which is pivoted a lever *15*, connected at its lower end with the upper edge of a cam member *16*, which has two straight parts that form an angle with sides *17*-*18* (Figures 10 and 34), for the purposes that will be described with more detail in the following paragraphs and, at the point of connection between the elements *15* and *16*, there is connected a second lever *19*, which, at its lower end, is connected to one end of a rocking member formed by two parallel rods *20* (Figures 10-11-35) which, by means of a pin *21*, common to both rods, are pivotally connected either to the lower part of partition *3* as shown in Fig. 33, or directly to a support *23*, at the end of which is connected for free rotative movement, the shaft *24*, that is connected to the eccentric *16*. The rocking member formed by the rods *20*, is connected at its opposite end to the upper end of a cam member *25*, that constitutes the driving means for the lower sliding member *26*. The member *26* is mounted for free sliding movement in lateral grooves, dovetail shaped, between guides *27*, fixed to the edges of a recess *28*, made in the lower part of partition *3* (Figures 1-6). During rotation of the cam member *16*, the sliding members *8* and *26* are actuated and moved in opposite directions. That is to say, they alternately ap-

proach and move away from one another. The elements *4*, *7*, *15*, *16*, *19*, *20* and *25*, constitute the driving means, for the vertical rectilineal and alternative movement of the sliding members *8* and *26*.

The sliding member *26*, carries a rotatable punch *29* at its upper end, guided by a support *30* (Figures 1-6) made solid with the sliding member, and in this support there is mounted with a free rotative movement within a bush *31*, a shaft *32*, (Figures 1-7) at the end of which the rotatable punch *29* is detachably connected. The shaft *32* is mounted in a supporting member, and adjacent to said member *33*, the shaft *32* carries a driving pulley *34*. The supporting member *33* forms an integral part with the lower portion of the sliding member *26*, in which portion is provided a lengthwise hole *35* (Figure 7) for slidably receiving a supporting stem and guide *36*, for permitting rectilineal alternative movement of the sliding member *26*. The said stem *36* is fixed at its lower end, through adequate fixing means, to a supporting member *37*, that projects from the lateral inner side of a cross bar *38*, between the front legs of frame *1*.

At the lower end of the sliding member *26*, there is fixed a pin *39* (Figures 7 and 10) to which is connected the lower end of a coil spring *40* which, at its other end, is connected to a hook member or the like *41*, fixed to a cross bar *42*, of frame *1*. The said spring *40* constitutes a compensation member for the rectilineal alternative displacement of the sliding member *26*.

The eccentric member *16* is connected through shaft *24*, to a gear wheel *43* (Figures 1-10-16-32-35 and 36) that meshes with a pinion *44*, driven by a second gear wheel *45* by means of coupling between the said elements *44*-*45* to a common shaft *46*, and the gear wheel *45* meshes, in its turn, with a driving pinion *47*, connected to a driving shaft *48*, passing through supporting and guiding bearings *49* and *50* (Figures 1 and 16). The first of these bearings is fixed to the inner part of the front side of the frame, and the second, to an intermediate supporting plate *51*, fixed between the lateral sides of frame *1*, towards the upper end of same and adjacent to its rear side, from which point shaft *48* projects to the exterior, carrying, fixed to its end, a driving pulley *52*, on which operates a flexible transmission element *53* connected and operated by a suitable source of power.

The transporting means for the shoe comprise a rack member *54* (Figures 2 and 12) which is driven by an angle lever formed by arms *55*-*56* (Figures 10 and 14) pivotally secured to the support *23*. The arm *56* carries a roller *57* (Figure 10) in contact with the surface of the eccentric member *16*, which through its cam-like portion *17*-*18* transmits to said lever member, the rocking alternative movement from right to left, and contrary, the said movement, being transmitted, through an additional arm *58* (Figures 12, 14 and 15) to the rack member.

The additional arm *58* is connected to the lever member arms *55*-*56*, and swung thereby on a shaft *59*, that projects from the partition *3* (Figure 14). The said arm *58* (Figures 12, 14 and 15) is provided with a forked end, in which enters, freely, a finger *60* (Figures 12, 14 and 15) from which projects a stem *61*, connected, towards the end of the rack member. The eccentric member *16* constitutes the means that serve for transmitting the rocking movement to both arms *55*-*56* that, in its turn, transmit that

motion to arm 55 and this to the rack member 54, in cycles of horizontal alternative movement, of a length equivalent to the distance between stitches, being the advance movement effected as a result of the operation on the roller 57 (Figure 10) by the edge 17, of the eccentric member 16. During return movement of the arms 55-56 the roller 57 rolls along the edge 18 under the influence of a coil spring 62 (Figures 10, 12 and 15) which, at one end, is secured to a knob 63 on the rack member 54, and at the other end is held by a pin (Figures 10, 12 and 15) that projects from the lateral side of partition 3, where same strikes against the knob 63.

In the front side of partition 3 and over the groove 65 that constitutes the guiding means for the movement of the shoe mould 66 (Figures 7 and 12) there is provided the plate 67, in the form shown more particularly in Figures 1-7 which, on its face normally directed to the rack member 54, is provided with a plurality of rollers 68, mounted between supporting elements 69, fixed at the upper and lower ends of said plate (Figure 4). The plate 67, by means of the anti-friction rollers 68, forms a pressing and guiding member for the shoe mould of the standard type, shown in Figure 12, and the same is fixed between the edges of the groove 65, with the aid of fixing plates 70, fixed to partition 3 by means of pins 73 (Figures 1-9) provided with knobs 72, which are clearly seen in Figure 9, the said pins 73 being counter operated by a respective expanding spring 71 (Figure 9) which works as a safety means.

With reference to the means feeding the thread at the final cycle of the sewing of each sole, these comprise a rod 74 (Figure 10) that is fixed by one of its ends 75 through a pin and slot connection 82-83, to a guiding rod 76, pivotally connected at one end through a pin 77 with partition 3 and at the other end the lower one, the said rod 76 is connected to a sliding member 78, mounted at the back of partition 3 between members 79 (Figures 10-13). The connection between the rod 76 and the sliding member 78 is established by a pin and slot connection 80-81. One end of a spring 85 is secured to the end 75 of the rod 74, which at its other end is fixed to a member 86, fixed to a rib 87, formed at the rear of partition 3 (Figure 10).

The rod 74 is adjustably connected to a support 88 (Figure 10) coupled with the arm 55, through an extending member fixed in a determined position, with the aid of any fixing means, a pin or the like, that is inserted within one of the sides of said arm 55.

The sliding member 78 is provided with a hook 89 (Figures 10-12) that works within a rectangular recess 90, made in the end zone of the rack member, opposite to that of the knob or step 63 for the purpose of connecting with the pawl 91 of the shoe mould 66 (Figure 12), for driving same with a rapid lineal movement at the end of the sewing cycle, providing a determined quantity of thread, for the final cycle of manufacture of the shoe, which cycle consists in sewing the ends of the thread that are left by the usual machines of heel and toe, regulating the length of free thread with the more or less extension of penetration of the rod 74 within the support 88.

With reference to the feeding and guiding means, for the sewing thread and the corresponding regulating means for the tension of the

thread to be delivered to the needle 11, these comprise (Figure 1) a rod 92 connected to the partition 3, in inclined position. This rod is provided at its upper end with an eye 93, through which passes the thread 94, coming from a feeding bobbin 95, placed, with the aid of a support 96, at any point, which plan may be, eventually the floor, as indicated by the earth line T-T of Figure 1.

The thread 94, after leaving the eye 93 of the rod 92, is inserted freely, between the tension regulating means constituted by some discs 97 (Figure 8), connected to a support 98, from which projects a pin 99.

The pin 99 is provided with a perforation 100, at its end adjacent to the support 98, and at a point between the discs 97. Through this perforation is inserted the thread 94 and both discs 97 are retained one against the other by means of a spring 101 (Figure 8) which, at its opposite end is engaged by knob 102.

The sewing thread 94, that passes through the perforation 100, in the pin 99, projects to an eye 103 (Figure 1), formed at the upper end of a rod 104, fixed, in partition 3, with the aid of any adequate retaining means, a pin or the like. From the eye 103, the sewing thread is projected to a second group of complementary tension regulating means. A cone shaped member 105 (Figures 1-9) is provided with a hole at 106, formed towards the rear end of part 107 of said member 105. A back member 108 is connected concentrically by means of a shaft or pin 109 to partition 3, having provided between partition 3 and the extended rear end 108, a spring 110, mounted axially on the pin 109, upon which pin the member 108 is threaded, which is kept in position by the permanent tension of said spring 110.

The member 105 is connected to the upper end of the plate member 70 (Figure 1) by means of a threaded stem 111 (Figure 9) that ends in a handling knob 112 and passing from perforation 106, the thread is projected to pass the eye provided at the upper end 113 of a guiding rod 114, fixed at the upper end of plate 70, and from its eye 113 the thread projects for penetrating within a guiding member 115 (Figure 1) that contacts with the turning surface of a pulley 116, mounted for free rotation at the end of an angular lever 117 pivotally connected at 119 to an extension 120 of an arm lever 121 that is, at its turn, pivoted to the sliding member 8 by means of a pin 122. The arm 121 is provided with a pin 125 mounted for freely sliding in an angular groove 123, of a retaining and guiding plate 124 (Figure 1). The plate is fixed at the front side of the partition 3 and adjacent to the sliding member 8.

The arm 118, of the lever 117-118, is connected to the extension of the lever 120, by means of a spring 126 (Figure 1) of regulable tension, depending on the point of attachment of its ends in any of the eyes 127 of the arm 118 or 128 of the arm 120.

Reverting to the driving means for the needle and punches, to the driving shaft 48 is fixed a complementary pulley 129, between the bearing 50 and the rear of the support or frame 1, (Figures 7 and 16) over which pulley runs, a flexible transmission belt 130 which, passes between a pair of lateral pulleys of smaller diameter 131, mounted for free turning on individual supporting and guiding shafts, provided on supporting members 132, fixed below the cross bar 51. The belt 130 also passes over a pulley 34, mounted on

shaft 32, for transmitting to same the rotative movement, simultaneously with its lineal rectilineal alternative displacement, jointly with the sliding members 8 and 26, as well as jointly with the intermittent displacement forward and backward, of the rack member 54, in a length equivalent to the distance between stitch and stitch, distance that is determined by the distance existing between the teeth with which meshes the pawl 91 of the mould 66 carrying the shoe (Figure 12) which is advanced, at intermittent cycles, by the meshing with the teeth of the said rack member until reaching the final tooth at this moment the stop 89 becomes operative, for transmitting to the pawl 91 and mould 66 the lineal quick movement of final advance, for leaving free a certain length of thread destined for the final operation of shoe manufacture in the usual machines of toe and heel.

Referring to the driving means for the shuttle of the common type, formed by the body 133 (Figures 10, 16, 17, 18 and 19) these comprise a transporting train formed by back and front toothed wheels 134—135 with the addition of a third wheel 136 (Figures 10—16) which is coupled in regulable position to a support member formed by a rod 137, adjustably secured in the frame 1, by means of fixing elements constituted by pins and nuts, and having interposed between said rod and the frame, a supporting bush 138 (Figure 10).

The wheels 134, 135 and 136, are connected to each other by a chain 139, in which and between two of its links, there is provided a pushing element 140 (Figure 16) disposed in cooperative relation with a complementary pushing stop 141, attached to the lower base of the shuttle 133 which, by means of longitudinal ribs 142 (Figure 19) is maintained over two rails 143, that constitute the guiding means for the lineal rectilineal alternative movement of the shuttle between said rails. The toothed wheels 134—135 turn in the free space provided between the opposite disposed edges of said rails, that are fixed to a supporting platform 144 (Figure 19) fixed to the upper part 2 of the frame 1.

Connection between the lower wheel 136 and the rod 137, is made by means of shaft 146, on which is mounted an intermediate bearing 145 (Figure 10). Said bearing 145, freely inserted in a longitudinal recess 147, is adjustably secured therein by the use of fixing means such as a safety nut or other adequate means.

The rod 137 is adjusted by a rod 148, (Figures 10 and 16) connected, transversally, to a pin 149 that projects, normally, from one of the faces of the rod 137, the said rod 148 being fixed to said pin by means of retaining elements, such as nuts 150. The other end of the rod 148 is pivotally connected to a support member fixed to the cross bar 38, that is secured transversally to the frame 1.

Referring to the driving means for the shuttle 138, they comprise a lever 152 (Figures 10, 16, 17 and 20) connected at its back end with free pivotal movement to a support member 153 that normally projects at one side of partition 3. The rod 152 is provided at its fore end, with a roller 154 (Figures 17 and 20) connected to same for free rotation on a shaft 155. The said roller constitutes the driving member for the shuttle. The said lever 152 comprises, at its end adjacent to the roller 154, a block of flexible material 156, fixed to same by means of a convenient fixing element, and the object of said block is to cushion

the impact of the lever against partition 3. Towards its back end, the said lever carries, in association therewith, either by direct coupling or with the use of an intermediate eye, a spring 157 (Figures 10—17) connected by its opposite end to the lower face of a plate 158, that normally projects from the partition 3, the said spring 157, constituting an operating means for the pulling lever 152 for the purpose that same, through a violent impact will return to the initial position the shuttle 133.

The wheel 134, forming a part of the transporting train for the shuttle 133, forms itself the driving means of the said train, and for that purpose, the shaft 159 of said wheel (Figure 17) is provided at the end with a pinion 160, that meshes with a similar pinion 161 connected to shaft 46, that forms the driving means of the transporting train, by way of its connection with the toothed member 44, which in its turn constitutes the driving means of the toothed wheel 43 that drives the eccentric 16. The shaft 159 is mounted in a bearing 162.

Referring now to the mechanism driving the shuttle, this is formed (Figures 16 and 17) with the provision at the fore end of the rails 143, of a metallic fence or cover, fixed at the end of said rails, and curved as at 164, corresponding to the sharpened end 133a (Figure 17) of the shuttle 133 and at the inner side of said fence at the curve shaped part 164, there is applied a lining of leather or similar material 165, that reduces the shuttle impacts.

The fixing of the fence 163 to the rails 143, is effected with the aid of a clamp 166 (Figure 17) provided between the front end of the side of the rails 143 and the open end 167, that projects from the curve shaped member 164, of the fence 163. The fence constitutes the member 40 that limits the shuttle race.

Referring to the pressing means, for the soles or the like, which form an integral part of the mechanism of the machine, these comprise (Figures 1, 7 and 22 to 31) a set of elements provided at the front side of the frame 1, and against a resting frame 168, to which is secured a protecting armouring 169, for the driving elements of the pressing means, as it is shown more specially in Figures 1 to 7, that show more clearly the arrangement of the pressing embodiment, the description of which will be made on the basis of the Figures 22 to 31. Over the lateral sides 168a of frame 168 is applied the table 169a, to the lateral sides of which are conveniently secured small supports 170, on the upper part of which is pivoted, at the ends, a shaft 171, to which is connected a lid 172, of variable shape, either for pressing sole moulds only or soles with toe piece and welt mounted on the corresponding mould, the said lid being shown diagrammatically in the accompanying drawings.

On the table 169a and symmetrically disposed in front, within respective cavities 173 and 174 (Figure 24) move the pressing members 175 and 176 (Figures 24—27) provided between sliding guides 177. These pressing members are provided with projections 178 and 179 (Figure 24) through which pass respective screws 180 and 181 (Figure 26) intended to be applied to angular plates 182 and 183, respectively, the edges of which press the running part of the mould, where the jute sole or canvas shoe is placed. The said screws 180 and 181 permit an exact adjustment for the approachment of plates 182 and

183, against the moving pressing elements of the mould.

The central part of the table 169a, carries a cavity 184 (Figure 24) in which is placed the mould which, for its insertion therein, is conveniently guided between lateral corresponding members 185 and 186 (Figures 26 and 27).

Below the lateral elements 188a of frame 188, there is conveniently fixed, the main driving shaft 187 of the pressing member, driven by the shaft 48 (Figures 23 and 25) of the driving mechanism of the machine.

This shaft 48 is provided with a worm 188, that meshes with a worm wheel 189, rotating continuously. Connection is established between said wheel and the shaft 187, in the form that will be explained in the following corresponding part of this specification.

On shaft 187 there are provided two eccentric members 190 and 191 (Figure 24), over which rest corresponding rollers 192 and 193, the first named of the rollers being mounted on an arm 194, pivoted at 195, the said arm being firmly united to another similar one 196, that carries at its inner end 197, pivoted at 199 to the ear 200, that is integral with the pressing element 175. Also the running pressing member 176 is connected in a similar manner through arm 201, coupled on a shaft 202, the said arm being rigidly united to a similar one 203, at the end 204 of which is connected a small arm 205, pivoted at 206, to the ear 207 of the running pressing element 176. The said arms 196 and 203 are double and are provided in pairs on respective bushes 208 and 209, coupled to the shafts 185 and 202 on the shaft 187, towards its ends, at both sides, there is provided an eccentric sector 210 (Figures 22 and 23) on which works a small roller 211 (Figure 22) supported by an arm 212, pivoted at 213, the said arm forming an integral part of a hook 214, intended to contact on a roller 215, connected to the lid 172, when this is in the position closed against the mould, the said hook having for its object, to maintain the lid in said position, because same tends to stand always in the raised position owing to the elastic action of spring 216, placed axially on the shaft 171 (Figure 27) on said lid.

The connection between the toothed wheel 189, and the shaft 187, is effected through the key 217 (Figures 23, 30 and 31) half round shaped, provided at the end with a stop 218, that projects at a right angle. Said key 217 is given a rotary angular movement when the stop 218 is operated to clutch and unclutch the wheel 189. Stop 218 works freely within a cavity 219 (Figure 29) provided in a bush 220, and tends always to remain in the position shown in Figure 31, by the action of a spring 221, fixed by one end to said stop and by the other end to a retaining member 222, that projects from the bush 220. As can be seen in Figure 31, the key, for the purpose of transmitting the motion, falls into grooves 223, provided in the worm wheel 189, on the contrary, when the key occupies the position shown in Figure 30, the worm wheel 189 can run freely over the shaft and the key without rotating same therewith.

For the purpose of retaining the key in the position shown in the said Figures 28 and 30, it is necessary to provide a stop that will, in its turn, engage and swing the stop member 218 of the key, and to that effect a retaining element 224 is provided (Figure 28). This element con-

stitutes the projecting end of an arm 225, that forms an integral part with a sliding member 226, conveniently guided, and from the end of which normally projects an arm 227, that constitutes another element for the retention of stop 218 of the key. The said sliding member 226 is pivoted to a rod 228, which in its turn, is pivoted to the end of an arm 229, pivoted at 230, over any fixed element, of the machine, and the said arm is rigidly connected to a second arm 231, pivotally connected with the end of a driving rod 232, that projects from a treadle 234 rocking on a support 235, fixed to the floor. The lid 172, in its turn carries pivoted at 236 a link 237 (Figures 22 and 28) pivoted to the upper end of a lever arm 238, pivotally connected at 239, and from this connecting point projects, normally, the additional arm 240, at the end of which is pivotally connected at 241 a link 242, to the other end of which is connected the upper end of a lever 243, pivoted medially at 244.

At the lower end of the lever 243 there is pivotally connected, a link 245 pivoted at the end 246, to a sliding rod 247, suitably guided in elements not shown. This rod constitutes a supporting means for a piece 248, acting as complementary retaining means for the stop 218, for causing the rotation or the unclutching key of the driving mechanism for the pressing means, as hereinafter described.

The operation of the pressing mechanism is as follows: When motion is imparted to the shaft 48, such motion is transmitted by said shaft through worm 188, to the worm wheel 189, that turns freely on the shaft 187, because the key 217, is in the position shown in the Figures 28-30. Also, at the initiation of the operation, the lid 172, is in the open position (Figure 28 full lines). As it has already been said, the operation for pressing the mould is effected in two steps. The first one is intended to reduce the width of the sole texture, to such extent, that it will become suitable for applying to the mould, and the second, for finishing up the pressure on the shoe mould. The position of the elements is at the initial cycle of the operation, that shown in Figure 28. When the mould is inserted into the cavity 184, of the table 169a, the movable elements are disposed in the position indicated as 249 in Figures 24 and 26.

In the first instance, for the initial cycle of the operation, the workman will press the treadle 234 in the direction shown by the arrow F' (Figure 28), forcing the rod 232 to descend as shown by the arrow F'' turning, the arms 231 and 229, pushing element 228, and forcing the sliding element 226 to slide, and thus the arm 225 will be carried to the position indicated with dotted lines in Figure 28. The retaining element 224 will move, jointly with the same arm, to the position shown in said Figure 28, releasing the stop 218 of the key 217 which, by the action of the spring 221, will be carried to the position shown in Figure 31, in other words, will permit the clutching of the toothed wheel 189 and of the shaft 187, because the key 217 will introduce itself in any of the cavities 223 of the wheel 189. Under these conditions shaft 187 will be set in motion, driving bush 220, and also stop 218 which, when reaching the position a of Figure 28, will strike the stop element 248, of the rod 247. This engagement will produce the turning of the key 217, again to the position shown in Figure 30, and will release the connection between the wheel 189 and shaft

187, so that the said shaft will stop and the wheel 189 will turn free.

During the rotation, the shaft 187 will have caused the rotation of the eccentrics 190 and 191 (Figure 24) which eccentrics will have moved to such an extent, that the peripheric surface of each, designed as *b* in Figure 24, will have made tangential contact with the rollers 192 and 193 respectively, and by this time the arms 196 and 203, will have moved pulling the sliding pressing means 175 and 176. This movement of the sliding pressing means, corresponds to the first step of the mould pressing, because the plates 182 and 183 will have pressed above the parts 249 of the mould, that contains the shoe, a pressing action that will be continued until the width of the sole is adequately reduced.

Once the mould has been inserted, it is necessary to continue the pressing, for obtaining the total compression of the mould, and for this purpose, the lid 72, is manually lowered and applied over the mould that carries the shoe, as indicated with the arrow *Fa* of Figure 28, and at the closing of the said lid, the lid will pull therewith its pivot 236, to the position *c* and the link 237 will occupy the position *d*; the lever formed by the arms 238 and 240 will rotate on the pivot 239, carrying its arm 240, to the position *e* and the rocking lever 243 to the position *f* (Figure 28) at which operation the rod 247 will be advanced, and the stop element 248 will occupy the position *g*, separating itself from the stop 218. Thus the stop 218 is released and by the action of the spring 221, will tend as formerly, to turn so that the key 217, will be again introduced in the groove 223 of the wheel 189, for again connecting the said wheel with the shaft 187 and drive this shaft again.

The rotation of shaft 187 will, as already said, turn the bush 220 and stop 218 of the key, and this will reach the position *j* of Figure 28, stopping at this position by the interposition into its path, of the arm 227 which, in the initial cycle, of the operation, had been carried to the position *h* of Figure 28. Thus the stop 218, will return to occupy the position shown in Figure 30, releasing again the wheel 189 from shaft 187.

During the cycle of rotation of shaft 187, which corresponds to the passage of the key 217, from the position *a* to the position *j* and corresponds to the second step of compression, the eccentrics 190 and 191 will have turned to such an extent, that the highest points of their periphery, will contact with the rollers 192 and 193 respectively, thereby causing the arms 196 and 203, to move to their maximum points *r* and *p* (Figure 24) giving the maximum compression to the pressing elements 175 and 176.

At the same time, while the above operation takes place, and at the end of it the sectors 210 on the shaft 187, have commenced their operation.

The peripheric surface of the sectors 218, at the moment this second step of the pressing operation, takes place have made a contact with the rollers 211, advancing the hook 214, and causing same to engage the roller 215, of the lid 172, so that the hook will keep the lid pressed against the mould, during the final compression of same by the pressing elements 175 and 176. Once that sector 210, has passed out of contact, with roller 211, the arm 212 and the hook 214 will fall by gravity, leaving the roller 215 and consequently the lid 172 which, by the action of the springs 216, will rise for occupying the position shown in Figures 27 and 28, carrying with it,

at this movement, the parts related to the retaining member 248, for placing same in its original position shown with full lines in Figure 28.

At this step of the operation, the lid 172 is in the raised position but the pressing members 175 and 176 are still pressing the mould, so that for withdrawing same, it will be necessary to withdraw the said pressing members. For this purpose it will be sufficient, to press the treadle 234 in the direction of the arrow *Fb* (Figure 28) which action will return to the initial position rod 232, arms 231 and 229 and rod 228, that is to say, sending back arm 227 from its position *h* jointly with arm 225 and stop 224, which will be moved to the position indicated with full lines in Figure 28.

The arm 227, having been withdrawn, free passage will have been provided for stop 218 that was stopped in position *j* (Figure 28) and which, by the action of the spring 221, will turn the key 217, for introducing same again in any of the notches 223, of the wheel 189, and connect the said wheel with the shaft 187. The stop 218 rotates with the shaft 187 into engagement with the element 224 and is thereby turned to inoperative position thus completing the pressing operation. The rollers 192 and 193 will keep applied to the related eccentrics by the action of a spring 250, connected by its ends (Figures 23 and 24) between supports 251, connected to the bushings 208 and 209, which spring also tends to separate the pressing elements 175 and 176.

The mould thus pressed, may be withdrawn and the pressing means prepared for a new pressing cycle, it being possible to effect the pressing operation of the mould in a single step, for which purpose it is only necessary to change the levers and the arms mechanism that drive the various retaining means, against stop 218, by other elements that will cause only two cycles of stopping to said stop, one in the position of the initial cycle of the operation, and the other in the position indicated as *j* (Figure 23).

As regards the means for braking the needle reference is had to same in Figures 7 and 16, and more particularly in Figures 32 to 39. The part 252, of the toothed wheel 43, is connected to shaft 46, by means of a key member 253 (Figures 35, 37 and 38) of half round cross section, that penetrates into a similarly shaped longitudinal cavity or slot 254, as shown in Figures 35-38 provided in the shaft 46. At the same time, the piece 252, of the said toothed wheel 45, is provided with a longitudinal slot 255, in which follows the key when turning (Figure 37). The said key 253 carries, on its end, an extension that normally projects in the shape of a stop 256, that moves within cavity 257, made within a bush 258, coupled to shaft 46, through a fixed key 259 (Figures 35-36). Stop 256 is, in normal working conditions, in the position shown in the Figures 32 and 36, and is held in that position by the pressure applied by the transmission of motion from the wheel 45 to the shaft 46 and the elastic action of a spring 260, that connects the end of the stop 256 with a pin 261 on the body of the bush 258. While stop 256 is in the position shown in Figure 37, as it will be gathered, the toothed wheel 45 carries the shaft 46 along with it, and when the said stop 256 is in the position shown in Figure 38, the key is completely withdrawn into the cavity 254 of the bush, and the toothed wheel 45 will freely rotate thereon. A handle 262 is connected by means of an

intermediate rod 263, to a lever member 264, pivotally connected at 265 to the table 2 of the frame 1; the said lever member forms integral part with a crank arm 266, that ends in a fork shaped part 267 (Figure 34) for the purposes 5 that will be explained hereafter.

The lever 264 is provided with a projection 268 (Figure 34) to which is pivoted at 269 a braking member formed by a plate 270, provided at its rear end with a handle 271. The relative 10 position of the braking member is determined by a spring 272 bound to same by one of its ends and by its other end to a guiding support 273, with the intervention of a roller 274, supported for rotation on the said guiding support 273. The roller 274 makes tangential contact on stop 275, that forms integral body with the braking member.

Over the toothed wheel 43 and at the same side with the braking member, there is applied a part 20 276 that presents a body normally projecting of the said wheel, providing a surface 277 that is, as will be seen, a lateral pushing member, for the purpose of producing the angular rotation of the braking member, when the same must work. Normally, the pushing member 276 rotates with the toothed wheel 43, since the working element is out of its path.

The operations of the device is as follows: Considering that the machine is in operation, the 30 various elements that form the braking mechanism will be in the position shown in Figures 32 and 33, and the machine continues its normal sewing operation, already specified through its needle 11, by successive rectilineal alternative movement of same.

When it is required to stop the operation of the machine for any reason, the operator must operate handle 262 (Figure 32) carrying same to the dotted position in said Figure 32, in which 40 position it will be held by action of a stop 278 (Figure 1) of a lever 279, that is pivotally connected towards the lower end of partition 3, adjacent to its lateral edge, it being possible to use any other fixing means suitable for the purpose.

When carrying the handle 262 to the position above explained, the arm 263 and the lever 264 will have moved to the respective positions indicated with dotted lines in Figure 32, and the braking member will have been carried to the 50 position s of Figure 32. In that position the braking member 270 will be engaged and shifted laterally by the rotating pushing member 276. At this moment, the surface 277, of the said pushing member 276, will make slight contact with the lateral surface 280 of the braking member, forcing same to the position t of Figure 32 and there, the step 281, provided at the end of the braking member, will engage the stop 256 and turn the key 253 to the position indicated at u in Fig. 32. Thus the connection between the wheel 45 and the shaft 46 is broken and the motion of the shaft is arrested. As will be understood, the position of the pushing member 276 is so chosen with respect to the wheel 43 and connection between the latter and the slide 8, that the motion is stopped when the slide is in the upper position of its course.

For restoring the braking mechanism to operative condition, it will be sufficient to return the 70 handle 262, to its initial position, jointly with the other elements that form the braking group; this action will carry the braking member 270 back, for releasing the stop 256, which will also return from position u to initial position under 75

the action of the spring 260. This will turn key 263 angularly, until reaching again the position shown in Figure 37, and as a consequence, the toothed wheel 45 will again be connected to shaft 46, for continuing the transmission of the movement.

With the machine at rest, if it is desired to move the sliding member 8 that carries the needle 11, this may be done by means of an emergency device, operated by hand, and which is formed by the following combination of elements: A pinion 282, that can mesh with the toothed wheel 43, is mounted on a shaft 283, provided with a collar member 284 (Figures 32 and 33) fixed to same and constituting an abutment for an expansion spring 285 which, at its opposite end, rests against a support 286, that constitutes the guiding member for the lineal rectilineal alternative movement of the shaft 283 in cooperation with the pinion 282. The said spring constitutes an element that tends to maintain the pinion 282 out of the meshing position, with the toothed wheel 43. Shaft 283 ends in a handle member 287, connected to said shaft by a crank arm 288.

For manually operating the driving mechanism of the needle 11, it is sufficient to push the shaft 283, rearwardly to an extent to mesh the pinion 282 with the toothed wheel 43, thereafter turning the crank 288 through handle 287, the said elements transmitting the rotative motion to pinion 282 which, in its turn, transmits motion to the toothed wheel 43 prior to rotary movement of the wheel 43, the pushing member 276 thereon maintains the braking member 270 in the position t, and the stop 256 in the position u of Figure 32, but when the toothed wheel 43, is rotated, the pushing member 276 will release the braking member 270 and this will be able to return to the position s under the influence of the spring 272 permitting stop 256 to return to the operative position, shown in Figure 32, by the tension of the spring 260, thus turning the key 253.

In order to prevent the gear wheel 45 from being thus coupled with the shaft 46, the handle 271 is swung in the direction indicated by the arrow Fd (Figure 32) the said action causing the stepped end 281 to thrust the stop 256 to the position v of Figures 32-35, at the bottom of the recess 257 and sliding the key 253 longitudinally, the opposite end of which (Figure 35) pushes the ring 289 to the position x.

Stop 256 is confined in the position v (Figure 32) by the recess 257 and permits hand driving to be accomplished with the use of the crank handle 288, whenever it will be required and when the driving of the crank handle 288 is finished, same will return, to its initial position by the action of spring 285, and the pinion 282 will be put out of meshing with the wheel 43.

For returning the machine to its normal operative condition, handle 262 must be carried from the position shown with dotted lines in Figure 32, to the one shown in said figure, with full lines, and thus the forked end 267 of the arm 266 displaces the ring member 289 from position x (Figure 35) and carries same to the position shown with full lines in the said figure. The said ring member will press on the end of key 253, pushing same forward and withdrawing stop 256 from the recess 255, to an extent that will place same in condition for returning to its original position, by the action of the spring 260. Thus the machine is restored to condition for normal operation.

Having now particularly described and ascer-

tained the nature of my invention and how same can be carried into practice, I declare that what I claim is:

1. In a machine for sewing shoe soles of jute and like material, a sole carrier movable step-wise and having a row of openings therethrough, slidable members arranged above and below said carrier, relatively displaced punches movable with the slidable members to penetrate said openings, a needle carried by one of said slidable members and displaced with respect to said punches, means for simultaneously reciprocating said slidable members, one of said punches being mounted to rotate in the related slidable member, and means for imparting rotary movement to said rotatable punch.
2. In a machine for sewing shoe soles of jute and like material, a sole carrier movable step-wise and having a row of openings therethrough, a slidable member arranged above said carrier, a punch carried by said member, a needle arranged in spaced parallel relation to said punch and secured to said member, said punch and needle being movable with said member to penetrate said openings, a slidable member arranged below said carrier, a shaft rotatably mounted in the second slidable member, a punch rotatable with said shaft and movable with the second slidable member to penetrate said openings, means for simultaneously reciprocating said slidable members, and means for imparting rotary movement to said shaft and the related punch.
3. In a machine for sewing shoe soles of jute

- 5 and like material, a sole carrier movable step-wise and having a row of openings therethrough, slidable members arranged above and below said carrier, relatively displaced punches movable with the slidable members to penetrate said openings, a needle carried by one of said slidable members and displaced with respect to said punches, a crank pin, a lever connected medially with said crank and connected at one end to the upper slidable member, a fixed pivotal mounting for the other end of said lever, a second lever pivotally mounted intermediate its end, one end of the second lever being connected with the lower slidable member and the other end being connected with said crank pin.
- 10 4. In a machine for sewing shoe soles of jute and like material, a sole carrier movable step-wise and having a row of openings therethrough, a slidable member arranged above said carrier, a punch carried by said member, a needle arranged in spaced parallel relation to said punch and secured to said member, said punch and needle being movable with said member to penetrate said openings, a slidable member arranged below said carrier, a shaft rotatably mounted in the second slidable member, a punch rotatable with said shaft and movable with the second slidable member to penetrate said openings, a pulley carried by said shaft, a flexible drive member engaging said pulley, and means for simultaneously reciprocating said slidable members.
